UNITED STATES PATENT OFFICE.

SIGURD SMITH, OF CHARLOTTENLUND, NEAR COPENHAGEN, DENMARK.

BEATING ENGINE.

Application filed March 17, 1921. Serial No. 453,040.

To all whom it may concern:

Be it known that I, SIGURD SMITH, subject of the King of Denmark, residing at Charlottenlund, near Copenhagen, Denmark, have invented new and useful Improvements in Beating Engines, of which the following is a specification.

The so-called Hollander, one of the most important machines of the paper industry 10 serves, as it is well known, to prepare the paper stuff before the latter is conveyed to the vat and from there to the wire cloth of the paper machine.

In spite of the great importance of this 15 machine in the paper industry, and its use during several hundred years, there has been, up to now, a remarkable want of understanding of the circumstances ruling its action and, consequently, the designer has 20 been in a difficult position when having to dimension the Hollander for a certain capacity and a certain quality. Numerous experiments were made in order to form a reliable theory for the Hollander, but up to 25 the present time, none of the theories proposed has proved itself to be reliable in practice.

By scientifically conducted deliberations 30 and a parallel series of experiments, as well as by a scientifically directed mathematical treatment of the material compiled in this manner, the applicant has succeeded in removing the darkness surrounding, up to now, the working of the Hollander, and in 35 forming a theory for the same in accordance with the results of the experiments.

The present invention relates to an arrangement adapted to increase the capacity of the Hollander, the said arrangement being 40 based upon the comprehension of the mode of action of this machine, which the applicant has arrived at, and the invention constitutes a technical result of this comprehension.

Before the invention may be described, a 45 short account of this comprehension must be given.

The treatment of the paper stuff in the Hollander has a double effect: In the first 50 place the individual fibres of the stuff are cut to a certain length shorter than the one they had in the raw material, in the second place the fibres are exposed to pressure in combination with a partial crushing and tearing action.

While it had not, up to the present time, been made clear how the stuff was enabled to assume a position favorable for being cut between the edges of the bars, nor how the stuff may be introduced between the 60 faces of the roll-bars and the plate-bars in such a manner that it will be exposed to a pressure and tearing action, the author has succeeded in clearing these questions. In the accompanying drawings Figs. 1, 2 and 3 show diagrammatically the action of roll bars and plate bars on the stuff. Figs. 4, 5, 6, 7 and 8 are broken and fragmentary sections through a machine, showing the application of various constructions of my invention. 70

The applicant has shown, in fact, that during the operation of the machine the fibres of the stuff adhere as a bundle to the front edges of the roll bars and, similarly, to the oppositely directed front edges of the plate bars as it is indicated, quite diagrammatically, in Fig. 1 which illustrates a cross-section of a roll bar *a* and a plate bar *b*, while the arrow *c* indicates the direction 80 of motion of the roll bar. The fibres *d* attach themselves as a bundle to the bar edges and, mainly, in a plane perpendicular to the axis of the bar roll, a position which the fibres will assume even on account of the downward motion of the roll bars in the stuff, as it appears from the following. 85

Suppose that in Fig. 2 the observer of the figure moves with the roll bars, and suppose that the arrows indicate the apparent 90 velocity of the stuff relatively to these bars, then it will be seen that the flow of stuff will be split by the downwardly directed bar edges, the result being that the fibres will attach themselves like a bundle to the bar edges, while the stuff slides partly in direction of the bottom face of the bar (i. e., in tangential direction) partly in direction of the front face thereof (i. e., in radial direction). In similar manner the motion in Fig. 95 3 may be conceived, this figure illustrating, in outline, a portion of a cross-section of the plate bars with two roll bars *a* moving above the same. When the observer follows the roll bars in their motion, the plate bars will appear, relatively to him, to move to the right in direction of the arrow at a speed equaling that of the roll bar. It will now be understood that the stuff contained in the cells between the roll bars will be set 100 105 110

in whirling motion in the direction of the arrow, and maintained in such motion, and the plate bars, while causing this motion, will catch a fibre bundle on their front edges 5 as indicated in the figure.

The present novel arrangement of Hollanders is based upon this novel comprehension of the actual co-operation of the roll bars, the plate bars and the fibrous stuff in 10 the machine.

It has frequently been attempted to attain an increased beating action by providing, in the Hollander, a considerable number of plate bars in the Hollander and then, as a 15 rule, in such manner that the plate bars were disposed in two or more groups at some distance from one another. Experience has shown, however, that a higher beating effect cannot at all be attained by increasing the number of plate bars beyond a 20 certain small number, and this suitable number depends somehow on the kind of stuff to be beaten in the Hollander. The reason why the beating effect cannot be increased 25 in this manner, is to be found in the fact that in case of the known plate bar construction the said stuff bundle hanging on the edge of the roll bar has no chance to be maintained or rather to be replaced, when 30 gradually worn away.

The invention has now for its object to provide such maintenance or renewal of the stuff bundles of the roll bars during the motion of the latter over the plate and, according to the invention, this object is to be attained by giving the front edges of the roll bars, at one or more points of the plate and with or without operation from the outside, a chance to have the stuff bundle replaced 35 when worn away, whereby the bars will be enabled to renew or repeat their action over the not yet passed portion of the plate.

This principle underlying the invention may be carried out in various manners.

45 One construction is illustrated in Figs. 4 and 5, the former showing a section of the Hollander at right angle to the bar roll axis, and the latter showing, on an enlarged scale, a portion of the plate.

50 As it will be seen, the plate in the illustrated construction is discontinued at centre, so that it forms two sections between which there is provided a recess which is closed at top by means of a diaphragm *h* fastened along its edges by means of a strip *i* attached by screws to the plate bar box. Below the diaphragm there is provided a beam *j* parallel to the bar roll axis, and to the top edge of this beam the diaphragm is 55 also fastened by means of a plate *k* secured by screws. At bottom the beam supports vertical guiding rods encircled by fixed guides, so that the beam may be moved up and down while maintaining constantly its 60 position parallel to the roll axis, the said 65

motion being effected by means of springs and a connecting rod. The connecting rod is driven by an eccentric disc or a crank on a driving shaft running below the plate. In this manner a faster or slower upward and 70 downward motion is imparted to the diaphragm and, thereby, the stuff contained in the space between the roll bars is set in vertically pulsating motion, while it passes over the diaphragm. By this pulsating motion 75 the stuff is caused to pass the front edges of the roll bars and, thereby, these front edges get an opportunity to catch a fresh stuff bundle.

Instead of the described driving mechanism an eccentric driving shaft provided below the diaphragm may be adapted to operate the same directly. The membrane may also be set in oscillation as desired by means of air or liquid being caused to oscillate below the same.

The same effect on the stuff may obviously also be attained by use of any other device anywhere in the plate, provided that this device be able to bring about a radial or partly radial motion of the stuff contained between the bars of the bar roll, so that an opportunity is offered the bars to pick up a fresh fibre bundle.

As an example of such arrangements 95 there is shown, in Fig. 6, a section of a portion of the plate, the said section being at right angle to the roll axis. Here no pumping device is used as in Fig. 5, but an agitating device is inserted between the two 100 groups of the plate. The agitating vanes are marked *l*, and the agitating shaft is marked *m*. The vanes will impart to the stuff a motion at right angle to the direction of motion of the roll bars in order to facilitate, thereby, the settlement of stuff fibres 105 on the front edges of the bars.

In Fig. 7 there is illustrated still another embodiment of the principle underlying the invention. Air is here blown into the stuff 110 contained in the space between the two plate halves, namely through holes *n* in the bottom part *q* between the two plate sections, and here the stuff is set in such motion that the roll bars get an opportunity to catch 115 fresh fibre bundles.

Besides, it might be practicable, at some suitable point of the plate, to pump stuff by way of a channel directly into the plate from the Hollander tank, or to introduce 120 the stuff in other manner. In this case, the plate bars may suitably be fixed in such a manner relatively to each other that the requisite supply channels will be formed simply in the spaces between the bars.

In the described constructions, the motion imparted to the stuff contained in the space between the bar roll and the plate is produced by operation from the outside. As it appears from the following, however, the 125

said desired motion of the stuff between the roll bars may be effected without any such operation from the outside.

As mentioned above, it has been attempted to increase the capacity by subdivision of the plate bars into two separate groups. Hereby, however, ordinarily no renewal of the fibre bundle will be attained, because the stuff contained between the two plate bar groups will find no opportunity to replace the stuff between the roll bars. It was demonstrated experimentally by Professor Haussner in his book entitled "Der Hollander," edited in Stuttgart, Germany in 1902, that the roll and the stuff contained in the bar spaces of the same and revolving together with the roll was only to a very slight extent able to set in motion the stuff contained in the space outside of the bars of the roll and, therefore, it must be assumed, in general, that along the cylinder surface dotted in Fig. 8 the revolving stuff will slide along the approximately stationary stuff in the space between the plate bar groups. Such sliding motion will be avoided if a smooth or bright plate be provided at such slight distance from the roll that the quantity of stuff filling the space will actually be forced, wholly or partially, to follow the motion of the roll, while the stuff slides on the said plate.

When now this plate is given a suitable shape, for instance the one shown on Fig. 8, where the distance of the plate from the roll is larger at centre than at the ends, the result will be attained that the stuff contained in the spaces between the roll bars will be partly extracted from the spaces between the bars by the rotation of the roll and, more specifically, until the stuff reaches the centre of the bright or smooth plate whereafter the stuff will again be conveyed into the said spaces, while the stuff moves from the centre of the smooth plate towards the second group of plate bars. Owing to this motion of the stuff in radial direction, simultaneously with the stuff being taken along by the roll bars, a fresh fibre bundle will become deposited on the front edges of the roll bars, this action being attained without any operation from the outside.

In the above constructions, it has been assumed that arrangements like those here described were to be used only at one single point of the plate. There is nothing to

prevent, however, that such devices might be used at several points of the plate, so that the effect of these devices may be repeated several times during the passage of the roll bars above the plate.

Having now particularly described and ascertained the nature of my said invention and in what manner the same is to be performed, I declare that what I claim is:

1. A bed plate for beating engine rolls having a grooved surface cooperative with the adjacent periphery of a beating roll, and means for discharging compressed air to said bed plate and between the opposed surfaces thereof and said beating roll.

2. In a beating engine the combination of a beating roll, a number of bed plates cooperative with the adjacent periphery of said beating roll, a recess between said bed plates, and means for causing movement in a direction to and fro the axis of the said roll of the stuff contained in said recess.

3. In a beating engine the combination of a beating roll, a number of bed plates cooperative with the adjacent periphery of said beating roll, a recess arranged between said bed plates and having a diaphragmatic bottom, and means for causing an oscillation of said bottom and thereby of the stuff contained in the recess in a direction to and fro the axis of the said roll.

4. In a beating engine the combination of a beating roll, a number of bed plates cooperative with the adjacent periphery of said beating roll, a recess arranged between said bed plates and having a diaphragmatic bottom and a rotating shaft causing an oscillation of said bottom and thereby of the stuff contained in the recess in a direction to and fro the axis of the said roll.

5. In a beating engine the combination of a beating roll, a number of bed plates cooperative with the adjacent periphery of said beating roll, a recess between said bed plates and a hollow bottom in said recess causing the stuff contained between the roll bars to first move away from the axis of the roll and later on towards same.

In testimony whereof I have affixed my signature.

SIGURD SMITH.
